OIL RANGE TOP CONSTRUCTION

Jacob Teller, Chicago, and Arthur P. Schulz, Hinsdale, Ill., assignors to G. & J. Teller, Chicago, Ill., a partnership composed of Grace Teller and Jacob Teller

Application June 15, 1938, Serial No. 213,904

4 Claims. (Cl. 126—44)

This invention relates to kerosene ranges.

Kerosene ranges as at present constructed essentially comprise a cooking top, a high oven at one side of the cooking top and a horizontal row of burners beneath the cooking top and the oven, with the row of burners extending along the front of the range throughout substantially the full length thereof.

Such ranges fail to meet present day requirements from the standpoint of compactness, cooking capacity and attractiveness in appearance for the reasons that in the present six lid, three burner cooking top and two burner oven, in which all burners are disposed in a single horizontal row, an unnecessarily long range for the cooking capacity thereof is required. Furthermore, such ranges fail to provide a plane working table top and thus lack in maximum efficiency as well as failing to present an attractive appearance.

It is a primary object of this invention to provide a kerosene range which is compact, provides maximum cooking capacity and is attractive in appearance.

It is a further object of the invention to provide a plane cooking top with a low oven disposed below the cooking top, and with the cooking top burners disposed on opposite sides of the oven.

It is a still further object of the invention to provide a kerosene range comprising a low oven with a pair of burners therefor, a plane cooking top comprising a pair of main cooking grids at each side of the oven and two pairs of auxiliary grids disposed above the oven, a burner being provided below each main grid and heat conveying ducts extending from the burners to the auxiliary grids.

For a more complete understanding of the nature and objects of the invention, reference will be had to the following detailed description, taken in connection with the accompanying drawing, wherein—

Fig. 1 is a perspective view of a kerosene range constructed in accordance with a preferred embodiment of the invention.

Fig. 2 is a front elevation of the range with parts thereof in section.

Referring to the drawing by reference characters, and wherein like characters designate like parts, F designates the supporting frame, and while this frame may be constructed of any desired form of material so far as the burner and grid arrangement is concerned, it is preferably formed of beaded molding whereby a more attractive appearance is offered by the complete range.

The frame F comprises opposite end members,

each being substantially of U-form and comprising a horizontal base support 10 and front and rear vertical members 11 and 12 respectively.

The upper ends of members 11 and 12 are suitably interconnected by a top rectangular member 13 at the rear of which is supported a splash back S and the base supports 10 are provided with suitable feet 14.

The frame member 13 removably supports four plates 15, each of which is provided with a main 16 grid and a somewhat smaller auxiliary grid 17, the main and auxiliary grids being disposed in pairs as will later appear.

Supported by the vertical members 11 and 12 adjacent the lower ends thereof is a shelf 18 which supports an oven burner compartment 19 having an oven 20 disposed thereabove with the top of same spaced a short distance below the auxiliary grids as is clearly indicated in Fig. 2.

The oven burners 21 are normally concealed by a suitable door 22 and are controlled by handles 23 mounted in a box like member 24 which encloses the pipe line and necessary mechanism for raising and lowering the bowls.

Supported by members 11 and 12 in connection with each side wall of the oven 20 is a box like member 25 each of which supports a pair of burners 26 and which are controlled by handles 27.

The burners 26 are arranged one beneath each of the main grids 16 as is more clearly indicated in Fig. 2 for directly heating same. The main and auxiliary grids 16 and 17 of each pair thereof are interconnected by a duct 28 with the respective burner 26 extending through the bottom thereof.

Thus it will be seen that the improved kerosene range in accordance with this invention comprises eight lids or grids and four cooking burners with a pair thereof disposed at each side of the oven and with the main grids being disposed above and directly heated by the burners and the auxiliary grids being disposed above the oven and being heated by means of the heat conveying ducts 28. With this improved arrangement, a cooking top of the table-top type is provided which has a maximum capacity due to the transverse disposition of the burners at each side of the oven and the arrangement of the auxiliary grids above the oven.

The main grids are serviceable for rapid cooking and the auxiliary grids for simmering or less rapid cooking, the ducts 28 providing different degrees of cooking heat and thereby permitting the use of otherwise wasted heat.

In order to prevent conduction of heat to the oven 20 an air space 29 is provided between the oven and ducts 28.

While we have disclosed but a single specific embodiment of our invention, same is to be considered as illustrative only, and not restrictive, the scope of the invention being defined in the subjoined claims.

What we claim and desire to secure by Letters Patent is:

1. An open kerosene range comprising a frame, a shelf supported by the frame adjacent the bottom thereof, an oven supported by the shelf centrally of the frame, a plane cooking top above the oven and projecting over the shelf, a horizontal burner supporting member disposed between the shelf and cooking top at each side of the oven, and a pair of kerosene burners for the cooking top supported by each of said members.
2. A range according to claim 1 wherein said cooking top comprises a pair of main grids adjacent each end thereof and two pairs of auxiliary grids above the oven, the main grids being disposed directly above the burners.

3. A range according to claim 1 wherein said cooking top comprises a main and an auxiliary grid associated with each of said burners, the main grids being disposed directly above the burners, and the auxiliary grids being disposed above the oven and in communication with said burners by heat conveying ducts.

4. A kerosene range comprising a frame, a shelf supported by the frame adjacent the bottom thereof, an oven supported by the shelf centrally of the frame, a plane cooking top supported by the frame above the oven and projecting over the shelf, a horizontal burner supporting member connected with the frame and disposed between the shelf and cooking top at each side of the oven, a pair of kerosene burners for the cooking top supported by each of said supporting members, and burner control handles in said supporting members.

JACOB TELLER.
ARTHUR P. SCHULZ.
